United States Patent Office.

JOHN H. BELLAMY, OF CHARLESTOWN, MASSACHUSETTS.

Design No. 4,250, dated July 19, 1870.

DESIGN FOR A BRACKET.

The Schedule referred to in these Letters Patent and making part of the same

To all whom it may concern:

Be it known that I, JOHN H. BELLAMY, of the city of Charlestown, in the county of Middlesex and State of Massachusetts, have originated and designed a new Pattern for a Bracket, of which the following is a full, clear, and exact description, reference being had to the accompanying photograph making a part of this specification.

My invention consists in so arranging emblems in open-work so as to show above the shelf A a space for glass or photograph, B, surmounted by a crown, C, together with cross-keys *g g*.

On the top of crown C is a globe, D, on the top of which is a cross, E, above which is an eye, F.

On the right of space B is a crook, H, and a cross, I. On the left of space B is a miter, three barred, J, together with an open book, K, the whole being inclosed in ornamental scroll-work below.

The shelf A is scroll-work, there being used as a support for the shelf A a square, L, and scroll-work.

What I claim as my invention, and desire to secure by Letters Patent, is—

The design or pattern for bracket herein set forth.
JOHN H. BELLAMY.
